DESIGN
FOR A
MEDALLION PEN.
WILLIAM BALL, INVENTOR.

Patented July 21. 1857

As. 918

William Ball, of New York, N.Y.

Letters Patent No. 918. Dated July 21st 1857.

The schedule referred to in these Letters Patent, and making part of the same.

To all whom it may concern:

Be it known that I, William Ball, of the City and State of New York, have invented or produced a new and original design or device for stamping Steel Pens and Pen-Holders, and I do hereby declare that the following is a full and exact description thereof, the same being illustrated by the accompanying drawings.

The object or design of my invention is the production of a design or device to be stamped or impressed upon Steel Pens or Pen Holders, as or like a Trademark, to distinguish them from others, and is intended to particularize an improved kind or class of such articles.

The design or device, as will be seen more plainly from the drawings, is a Profile Head of Franklin, within a Medallion, which is to be struck or impressed upon the Pens, just above the termination of the nibs or elastic parts of the Pens, and at the lower end of that part of the Pen, which is intended for insertion into the Holder. In the case of its use upon Pen Holders, it may be impressed on any part desired; but generally upon the upper side of the holder—that is the side which is uppermost when the Pen is placed in the Holder, and held in the hand in proper position for writing— and just above the part holding or grasping the Pen.

This device when stamped or impressed upon the Pen or Pen Holder, will be a little above the level of the general surface of the Pen or Holder, in bass relief, but the extent or degree of relief may be varied as wished.

Upon the top and bottom of the Medallion is an extension, in a scroll or other shape, for inscribing the name of the Pen or Holder; the extension and place of inscription will be seen by reference to the drawing. The whole effect or appearance of the device and inscription is also apparent by inspection of the drawing.

Des. 918

DD

I do not have any reference to the kind or shape of the Pen, upon which this design or device is to be stamped, or impressed, but
What I claim as my Invention or production, and
desire to secure by Letters Patent, is the device above described, viz; a Head
or Profile likeness of Franklin, within a Medallion, for stamping or mark-
ing Steel Pens and Pen Holders.
